United States Patent Office

Des. 181,971
Patented Jan. 28, 1958

181,971

BOTTLE OR SIMILAR ARTICLE

Daniel Goldstein, New York, N. Y., assignor to Schenley
Industries, Inc., New York, N. Y., a corporation of Delaware

Application April 18, 1957, Serial No. 45,792

Term of patent 14 years

(Cl. D58—6)

Fig. 1 is a side elevational view of a bottle or similar article showing my new design,

Fig. 2 is an end elevation thereof,

Fig. 3 is a top plan view thereof, and

Fig. 4 is an elevational view of the other side thereof.

I claim:

The ornamental design for a bottle or similar article, substantially as shown.
